UNITED STATES PATENT OFFICE.

CHARLES L. HEISLER, OF SCHENECTADY, NEW YORK.

LOCOMOTIVE-TENDER.

1,186,777.

Specification of Letters Patent. Patented June 13, 1916.

Application filed September 2, 1915. Serial No. 48,631.

To all whom it may concern:

Be it known that I, CHARLES L. HEISLER, a citizen of the United States, and resident of Schenectady, county of Schenectady, and 5 State of New York, have invented certain new and useful Improvements in Locomotive-Tenders, of which the following is a specification, and which are illustrated in the accompanying drawings, forming a part 10 thereof.

The invention relates to improvements in the coal bin of a locomotive tender, and to improved means for moving the coal forwardly in the bin to bring it within convenient 15 reach of the fireman.

The invention herein shown is of the same general character as the invention shown in my pending application Serial No. 48,630, its object being to provide a different form 20 of construction of an adjustable shoveling platform for the fuel bin of the tender, and of the operating mechanism for driving the coal pusher.

The invention consists in a structure such 25 as is hereinafter described, and as illustrated in the accompanying drawings, in which—

Figure 1 is a detail vertical central section of a locomotive and its tender with the invention applied; Fig. 2 is a detail section 30 on the line 2—2 of Fig. 1; Fig. 3 is a detail plan view of the tender; and Fig. 4 is a detail plan section of the pusher operating mechanism.

The side wall of the fuel bin of the tender 35 is represented at 10, and its rear inclined wall at 11. The floor 12 of the tender extends forwardly from the rear wall 11, and there is provided a shoveling platform 13, hingedly connected to the floor 12 at 14, and 40 having an upwardly flexing joint 15. At each side of the forward section of this platform, and secured thereto at or adjacent to the joint 15, there is a hook 16 adapted to take over a stud 17 projecting inwardly 45 from the side wall 10. A second hook 18 is attached to the forward section of the platform 13 and adjacent its forward edge, being adapted to engage a stud 19 fixed in the side wall 10 and serving as an additional 50 support for the platform when in its elevated position. By disengaging the hook 18 from the stud 19, and the hook 16 from the stud 17, the platform may be lowered to the floor 12. The joint 15 may be so formed as 55 to serve as a stop to limit its downward flexure and thereby serve as an additional

support for the forward section of the platform when elevated to its extreme limit.

The mechanism provided for advancing the coal to the shoveling platform comprises a head 20, adapted to reciprocate over the tender floor 12, its width being substantially the same as the bottom of the bin,—a plate 21 extending backwardly from the upper edge of the head, and downwardly projecting side flanges 22, 23, and a rear flange 24 for strengthening the pushing element and excluding coal from beneath it. The flange 24 rests and slides upon the rear inclined wall 11 of the fuel bin.

Within the rear end of the pushing element there is securely fixed a cross-bar 25, which preferably extends its entire width. A pair of links 26, 27, connect the cross-bar 25 with a nut 28, in threaded engagement 75 with a screw-rod 29 which is journaled at its upper end in a box 30, securely attached to the wall of the fuel bin. A worm gear 31 is keyed upon the upper end of the screw-rod 29, and meshes with a worm shaft 32 80 extending horizontally and journaled in suitable boxes 33, 34, fixed to the fuel bin wall. A pair of bevel gears 35, 36, are loosely mounted on the shaft 32, and are in constant engagement with a bevel gear 37, 85 driven by a suitable motor (conventionally shown at 38 as a steam turbine).

A double faced clutch 39 is splined upon the shaft 32 between the gears 35, 36, and is adapted to lock them to the shaft 32 in alternation for the purpose of advancing and retracting the pusher head. A shipper lever 4, in the form of a bell crank, cooperates with the clutch element 39, and is pivoted at 41 to the tender wall. A rod 42 90 connects the free arm 43 of the shipper lever with the nut 28, and is in sliding engagement with the latter, being provided at its lower end with a head 44. Preferably the connection between the rod 42 and the lever arm 43 is by means of a knuckle 45, pivoted to the lever and secured to a guide rod 46.

As the pusher head approaches the limit of its forward movement, the nut 28 engages the head 44, thereby swinging the shipper lever on its pivot and engaging the clutch with the gear 36, thus causing the shaft 32 to be reversed in its direction of movement for the purpose of retracting the pusher head. As the pusher head approaches the limit of its backward movement the nut 28 engages the knuckle 105

45 and swings the shipper lever on its pivot to engage the clutch member with the gear 35, and thereby again cause the advance movement of the pusher head. A pull rod 5 47, connected to the shipper lever by means of a link 48 and bell-crank 49, affords means for changing the direction of movement of the pusher head at the will of the operator. A suitable housing 50 covers the 10 gear mechanism, shipper lever and screw-rod, and a housing 51 covers the links 26, 27, and the nut 28, and slides within that part of the housing 50 which incloses the screw rod. Steam may be led to the motor 15 38 by any suitable piping, such as shown at 52, and a throttle valve 53 may be controlled by a valve rod 54 extending to the forward end of the tender where it will be convenient of access.

20 I claim as my invention—

1. A locomotive tender having a fuel bin, a fuel pusher comprising a reciprocable head, a screw-rod journaled on the fuel-supporting wall of the bin for actuating the 25 head, and a worm gear for turning the screw.

2. A locomotive tender having a fuel bin, a fuel pusher comprising a reciprocable head, a nut connected with the head, a 30 screw-rod journaled on the rear wall of the bin and engaging the nut, and means for turning the rod.

3. A locomotive tender having a fuel bin, a fuel pusher comprising a reciprocable 35 head, a nut connected with the head, a screw-rod journaled on the rear wall of the bin and engaging the nut, and a worm gear for turning the rod.

4. A locomotive tender having a fuel bin, 40 a fuel pusher comprising a reciprocable head, a nut connected with the head, a

screw-rod journaled on the rear wall of the bin and engaging the nut, a gear on the screw-rod, a worm shaft engaging the gear, and a fluid motor for turning the shaft. 45

5. A locomotive tender having a fuel bin with an inclined rear wall, a shoveling platform at the forward end of the bin and elevated above the floor thereof, an inclined apron leading from the floor of the bin to 50 the platform, a fuel pusher reciprocable over the inclined wall and the floor of the bin, and worm gearing for actuating the pusher.

6. A locomotive tender having a fuel bin, 55 a reciprocable fuel pusher, power means for driving the pusher including reversing gears, and means actuated by the pusher at the end of each of its strokes for reversing the gears.

7. A locomotive tender having a fuel bin, a fuel pusher, a screw-rod engageable with the pusher, a driving shaft geared to the rod, a power shaft, reversing gears connecting the power shaft with the driving shaft, 65 a shipper lever for reversing the operative connection between such shafts, such lever being engageable by an appurtenance of the pusher at the end of each stroke of the pusher. 70

8. A locomotive tender having a fuel bin, a fuel pusher, a screw-rod engageable with the pusher, a driving shaft geared to the rod, a power shaft, reversing gears connecting the power shaft with the driving 75 shaft, a shipper lever for reversing the operative connection between such shafts, such lever being engageable by an appurtenance of the pusher at the end of each stroke of the pusher, and supplemental means for 80 manually controlling the shipper lever.

CHARLES L. HEISLER.
